HAROLD F. SHEPHERD, OF GROVE CITY, PENNSYLVANIA, ASSIGNOR TO BESSEMER GAS ENGINE COMPANY, OF GROVE CITY, PENNSYLVANIA, A CORPORATION OF PENNSYLVANIA.

WATER AND FEED PUMP FOR HYDROCARBON-ENGINES.

1,165,028.

Specification of Letters Patent. Patented Dec. 21, 1915.

Application filed August 12, 1914. Serial No. 856,392.

To all whom it may concern:

Be it known that I, HAROLD F. SHEPHERD, a citizen of the United States, residing at Grove City, in the county of Mercer and State of Pennsylvania, have invented new and useful Improvements in Water and Feed Pumps for Hydrocarbon-Engines, of which the following is a specification.

This invention relates to water and feed pumps for hydrocarbon engines and consists in certain improvements in the construction thereof as will be hereinafter fully described and pointed out in the claims.

With some types of hydrocarbon engines, it is desirable to feed a certain amount of water with the fuel. The amount of water necessary to feed varies with different fuels.

The object of the present invention is to provide a pump in which the proportions of fuel and water may be varied so that the proportions of water and fuel may be regulated as desired. This is accomplished preferably with the mechanism in which not only the proportions of water and fuel may be varied but the quantities of fuel may be varied without varying the proportions of water and fuel, in other words, the device is capable of use where a governing means is used in connection with the fuel varying the quantity pumped.

The invention is illustrated in the accompanying drawings as follows:

Figure 1 shows a side elevation, partly in section, on the line 1—1 in Fig. 2. Fig. 2 a section on the line 2—2 in Fig. 1. Fig. 3 a section on the line 3—3 in Fig. 2.

1 marks the fuel pump barrel, 2 the water pump barrel, 3 the fuel pump rod and 4 the water pump rod. The fuel pump rod 3 is connected with the cross head 5 and the water pump rod 4 with a head 6. The heads 5 and 6 slide in guides 7 and 8 arranged in the frame 9. The barrels 1 and 2 are preferably secured to this same frame so that the parallel alinement of the rods is maintained. A connecting rod or pitman 10 is connected with the cross head 5 in the usual manner and gives motion to the fuel pump rod 3. Ordinarily this would be connected directly to the fuel pump rod because the fuel chamber is subjected usually to much higher pressure than the water pump. A bearing projection 11 is arranged on the

head 5 and a similar projection 12 on the head 6. The projection 11 has a bearing 13 and the projection 12 a bearing 14. The pins 15 and 16 are placed in the bearings 13 and 14 respectively. These pins have flattened ends formed by milling off the pins forming two opposing parallel surfaces. This forms a small shoulder between the flat surface and the body of the pin and the shoulders at the opposite ends of the pins are in alinement with the surfaces of the projection 12. The lever 18 is provided with the forked ends 19, the forked ends fitting the surfaces 17 of the pins 15 and 16. The lever 18 is provided with double sets of arms so that the pins 15 and 16 are engaged at both ends, the forked ends 19 being of a size to fit the flattened surfaces lock the pins in position in the bearings. The forked ends afford a sliding connection between the lever and the heads 5 and 6 and the pins being free to rotate in their bearings form a pivotal connection so that the connection as a whole is a sliding and pivotal connection.

The lever 18 is mounted on a pin 20 preferably between the rods. The pin 20 is eccentrically mounted on a carrier 21. The carrier 21 is journaled in a bearing 22 in the frame 9. A clamp bolt 23 is provided by means of which the carrier 21 may be locked in any position. A handle 24 extends from the carrier by means of which the carrier 21 will swing so as to throw the pin to the adjusted position desired and when adjusted the pin may be locked in the adjusted position by means of the bolt 23 operating on the carrier 21. It will be observed that as the pin 20 is swung toward and from either the rod 3 or 4 that the fulcrum of the lever 18 is thus moved and consequently the lever is shortened with relation to one rod and lengthened with relation to the other rod. In this way, the throw or travel of one rod relatively to the other may be varied as desired. At the same time if the travel of the fuel pump rod 3 is varied as under the influence of the governor, the travel of the rod 4 controlling the water pump is similarly varied so that while the quantities may be varied the proportions remain constant. In this way the proportions of water and fuel may be adjusted so as to accommodate different qualities of fuel and when once ad-

justed will take care of various adjustments in the quantity of fuel maintaining with varying quantities a constant proportion.

What I claim as new is:—

- 5 1. In a water and feed pump for hydro-carbon engines, the combination of a fuel pump rod; a water pump rod; a lever connected to both rods; a fulcrum for the lever; and means for shifting the fulcrum to vary the relative throw of the lever at its connections with said rods whereby the proportions of fuel and water may be varied and the proportions maintained as the quantity varies.
- 10 15. 2. In a water and feed pump for hydro-carbon engines, the combination of a fuel pump rod; a water pump rod; a lever connected to both rods; a fulcrum for the lever arranged between the rods; and means for shifting the fulcrum to vary the relative throw of the lever at its connections with the rods whereby the proportions of fuel and water may be varied and the proportions maintained as the quantity varies.
- 20 15. 3. In a water and feed pump for hydro-carbon engines, the combination of a fuel pump rod; a water pump rod; a lever connected by sliding and pivotal connections to both rods; a fulcrum for the lever; and means for shifting the fulcrum to vary the relative throw of the lever at its connections with the rods whereby the proportions of fuel and water may be varied and the proportions maintained as the quantity varies.
- 25 15. 4. In a water and feed pump for hydro-carbon engines, the combination of a fuel pump rod; a water pump rod; a lever connected by sliding and pivotal connections to both rods; a fulcrum for the lever arranged between the rods; and means for shifting the fulcrum to vary the relative throw of the lever at its connections with the rods whereby the proportions of fuel and water may be varied and the proportions maintained as the quantity varies.
- 30 15. 5. In a water and feed pump for hydro-carbon engines, the combination of a fuel pump rod; a water pump rod; a lever connected to both rods; a fulcrum for the lever; and a carrier on which the fulcrum is mounted, said fulcrum being eccentric to the carrier so that the fulcrum may be shifted by swinging the carrier to vary the relative throw of the lever at its connections with

said rods whereby the proportions of fuel and water may be varied and the proportions maintained as the quantity varies.

6. In a water and feed pump for hydro-carbon engines, the combination of a fuel pump rod; a water pump rod; a lever connected to both rods; a fulcrum for the lever arranged between the rods; and a carrier for the fulcrum, the fulcrum being eccentric to the carrier whereby the fulcrum may be shifted by swinging the carrier.

65 7. In a water and feed pump for hydro-carbon engines, the combination of a fuel pump rod; a water pump rod; a lever connected to both rods; a fulcrum for the lever arranged between the rods; a carrier for the fulcrum, the fulcrum being eccentric to the carrier whereby the fulcrum may be shifted by swinging the carrier; and means for locking the carrier in adjustment.

70 8. In a water and feed pump for hydro-carbon engines, the combination of a fuel pump rod; a water pump rod; bearings mounted on said rods; pins in said bearings with flattened ends, the flattened ends forming shoulders on the pins; a lever having forked ends forming a sliding connection with the flattened ends of the pins, said lever operating on the shoulders formed by the flattened ends of the pins for locking the pins in the bearings; and a fulcrum for the 85 lever.

75 9. In a water and feed pump for hydro-carbon engines, the combination of a fuel pump rod; a water pump rod; bearings mounted on said rods; pins in said bearings 90 with flattened ends, the flattened ends forming shoulders on the pins; a lever having forked ends forming a sliding connection with the flattened ends of the pins, said lever operating on the shoulders formed by 95 the flattened ends of the pins for locking the pins in the bearings; a fulcrum for the lever; and means for shifting the fulcrum to vary the throw of the lever at points operating on said pins.

100 In testimony whereof I have hereunto set my hand in the presence of two subscribing witnesses.

HAROLD F. SHEPHERD.
